UNITED STATES PATENT OFFICE

LOUIS B. LINKMAN, OF CHICAGO, ILLINOIS, ASSIGNOR TO M. LINKMAN & CO., OF CHICAGO, ILLINOIS, A CORPORATION OF ILLINOIS

PIPE

Application filed April 11, 1932. Serial No. 604,553.

This invention relates to smoking pipes of the kind described in applicant's Patent No. 1,487,867, issued March 25, 1924, in which the mouthpiece of the pipe has projecting from its inner end a metal element which extends into the bore of the stem of the pipe bowl. These metal elements which are more or less tubular in form, serve to secure the mouthpiece to the pipe stem, and sometimes are so formed at their ends to be serviceable for scraping carbon deposits from the inner surface of the bowl.

The purpose of the present invention is to provide improvements in the metal connecting means between the mouthpiece and the body of the pipe.

In the drawing:

Figure 1 is a longitudinal sectional view of the smoking pipe.

Fig. 2 is a side view showing the mouthpiece and metal reinforcement separated from the tobacco holding part of the pipe, the latter being shown partly in section.

Fig. 3 is an enlarged sectional detail as indicated by the line 3—3 of Fig. 2.

Pipes of the type illustrated generally are made of briarwood with reference to the body or bowl part of the pipe, and the mouthpiece is moulded vulcanite. The end of the mouthpiece which abuts the body part of the pipe carries, in an enlargement of its bore, a metal element which projects into the stem of the bowl portion of the pipe.

These metal elements are useful in making a good connection between the mouthpiece and bowl, strengthen the pipe where breakage generally occurs, and provide a surface upon which moisture may condense and deposit stain or fine particles carried by the smoke, and are useful for cleaning the pipe, such as removing carbon encrusted on the inside of the bowl.

The present construction follows the same general plan but the metal nipple extending from the mouthpiece is formed to exactly fit a tapered bore in the stem of the pipe, is recessed at two points, or squared off to provide edges for scraping the surface of the bore when removed therefrom, and adjacent to the butt end of the mouthpiece is a spiral

ridge or square thread for fitting a similar coarse internal thread cut in the bore of the stem. The mouthpiece may be removed or inserted by turning it along the thread approximately one-and-one-half turns, and when thus removed it carries out condensate and sediment from the bowl stem. It is also formed at its end to serve as a cleaning tool for the bowl.

Referring to the drawing, the body of the pipe comprises a bowl 1 and stem 2, the latter having a tapered bore 3, terminating near the bowl, and connected with the tobacco space 4 of the bowl by a small passageway 5. The tapered bore is formed to provide for a square internal thread 6, near the end of the bowl stem.

The mouthpiece 7 is bored out at 8 to receive a metal member 9, and has the usual small smoke passageway 10 in line with passageway 11 in member 9.

The metal member 9 is cemented in the mouthpiece 7 so the two turn together when screwed into or out of the pipe, the member 9 being threaded at 12 to fit the thread 6. Two offset cuts 13 and 14 are made on opposite sides of member 9 leaving an intermediate portion 15 fitting bore 3. Portion 15 is perforated at 16 for the passage of smoke. The end 17 of the member 9 is tool shaped for cleaning bowl 1 at which time mouthpiece 7 serves as the tool handle.

Although but one specific embodiment of this invention is herein shown and described, it will be understood that details of the construction shown may be altered or omitted without departing from the spirit of this invention as defined by the following claims.

I claim:

1. A smoking pipe, the body of which consists of a bowl and stem, the latter being provided with a bore tapered inwardly, the outer end of said stem having a coarse, square internal thread, and the mouthpiece having a passageway therethrough and an enlarged bore at the end of the mouthpiece adjacent the stem of the bowl, a metallic member fitting the enlarged bore of the mouthpiece which is cemented to said mouthpiece and is provided with a thread for fitting the thread

- of the bowl stem and otherwise fits the tapered bore of the bowl stem except that it is cut away on one side at its end, and is cut away at another point offset from the end
6 cut to leave an intermediate portion which fits the bore of the bowl stem, said intermediate portion being perforated, and said metal element also having a passageway in line with the passageway of the mouthpiece.
10 2. A smoking pipe, the body of which consists of a bowl and stem, said stem having a tapered bore and provided with an internal thread near the outer end of the stem, a mouthpiece having a passageway there-
15 through, and an enlarged bore at the end of the mouthpiece adjacent the stem of the bowl, a metallic connecting member having one end fitting and secured in the enlarged bore of the mouthpiece, the part of said metallic connect-
20 ing member projecting from the mouthpiece being tapered to fit the bore of the bowl stem and having an external thread for engaging the thread of the bowl stem, said metallic connecting member being cut away on one side
25 at its end and being cut away at another point inwardly from the end cut leaving an intermediate portion fitting the bowl stem bore and dividing the bowl stem bore into two compartments, said intermediate portion having an inclined perforation, and said connect-
30 ing element also having a passageway communicating with the passageway of the mouthpiece.

Signed at Chicago in the county of Cook
35 and State of Illinois this 9th day of April,
1932.

LOUIS B. LINKMAN.
